UNITED STATES PATENT OFFICE.

JAMES H. WHITE, OF NEW YORK, N. Y., ASSIGNOR TO THE MANHATTAN BRASS COMPANY, OF SAME PLACE.

FIREPLACE-FRAME.

SPECIFICATION forming part of Letters Patent No. 513,255, dated January 23, 1894.

Application filed April 6, 1893. Serial No. 469,332. (No model.)

To all whom it may concern:

Be it known that I, JAMES H. WHITE, a citizen of the United States, residing in the city and State of New York, have invented an Improvement in Fireplace-Frames, of which the following is a specification.

Ornamental grate fronts have been made use of in which a metal frame is surrounded by ornamental tiling, and the grate is either supported by the metal frame or else set upon feet and resting within the fireplace. In this class of fireplaces it has heretofore been difficult to prevent the gases from a coal fire or the smoke from a wood fire passing out into the room, and under all circumstances a separate blower or screen is inconvenient on account of the space occupied by it when removed, or else it is objectionable in appearance. Efforts have been made to employ a rolling curtain of asbestos or similar non-combustible material, but this is liable to flap backward and forward by the currents of air and is also objectionable in appearance at the upper part of the grate frame.

In my improvements I make use of an ornamental hood coming out at the top portion of the grate frame, and within this a spring roller is introduced having a curtain of asbestos or similar material, so that the hood becomes an ornamental inclosure for the curtain and it also prevents gases or smoke passing out into the room, and the vertical edges of the fireplace frame are made double to form slots that receive the edges of the curtain of asbestos or similar material that hangs from the spring roller within the hood. By this improvement the edges of the curtain are held so that they do not flap back and forth or the curtain draw into the chimney or swing outwardly; the spring roller is substantially out of sight; the whole device is highly artistic and ornamental, and the curtain can be used either as a blower for directing the draft through the fire either within a grate or when wood is supported by andirons; or the curtain can be used for regulating the ventilation passing up the chimney, or be more or less ornamental upon the surface thereof so as to form, when drawn down, a summer-piece acceptable in appearance.

In the drawings, Figure 1 is an elevation of the improvement. Fig. 2 is a vertical section in larger size of the same, and Fig. 3 is a sectional plan view in still larger size representing the channeled edge of the fire place frame at one side.

The border or tiling A is of any desired character, and there may be a metal lining to the fireplace, a part of which is shown at B, and in front of the same is the ornamental frame C which may be of sheet brass or other material, preferably double with a back bar C' to form the channels D for the edges of the curtain E; or the ornamental frame C may be otherwise constructed or connected around the fireplace, the proper channels being left between the ornamental frame and the metal bars C' or fireplace front, and at the top of the fireplace is the hood F, projecting in front of the metal frame and made with end pieces 70 2 and curved top deflector 3, both of which may be more or less ornamental, and the hood is connected with the framework of the fireplace, and within the hood F is the spring roller G for the curtain E. This spring roller 75 is of any suitable character, and the curtain E is preferably of asbestos so as to be fire-proof, and the position of the spring roller G and the width of the curtain are to be such that the vertical edges of the curtain run 80 freely in the channels D, but they are held so that the curtain is retained in its proper position when drawn down more or less in front of the fireplace, and it is advantageous to make use of a bar 4 at the bottom edge of 85 the curtain and permanently connected thereto, the ends of which bar 4 are received into the channels D, and the curtain is thereby stiffened at the bottom edge so that it may be used either as a blower to a wood or coal fire 90 or for retaining any gases or smoke and preventing the same passing into the room, or the curtain may be drawn down to a greater or less extent for the purposes of regulating the ventilation through the chimney, and the 95 surface of the curtain may be ornamented to any desired extent so as to adapt the same to use as an ornamental summer-piece for closing the fireplace.

The fingers at H are connected at their outer 100

ends to the frame and extend toward each other to a greater or less distance or may be in the form of a bar extending all across and being in front of the curtain and at the upper ends of the channels that receive the edges of the curtain; such curtain is held in position by such fingers or cross bar and guided in its movements up or down. It is advantageous to extend the back of the hood downwardly as at L to near the fingers or cross bar, so as to close a space that otherwise might allow gases or smoke to escape.

I am aware that rolling curtains or blowers have been employed with grates and fire places, and that in some instances the edges of the blower have been guided by the grate frame, but these devices have been heavy and cumbersome and in many instances the grate frame and mantle had to be especially constructed so as to contain the rolling curtain. In my improvement the grate frame and hood being of sheet metal are light and can easily be secured in the fire place or to one already constructed, and they are especially adapted to fire places surrounded with tiles, because such hood and frame occupy but little space and are light and ornamental in character.

I claim as my invention—

1. The combination with the roller and curtain having a cross bar at its lower end, of an ornamental frame having channels at its opposite edges for the edges of the curtain and the ends of the cross bar, a sheet metal hood having a top and ends and projecting in front of and connected to the grate frame and receiving within it the roller and curtain, and the fingers or cross bar H, to guide the curtain, substantially as specified. 30

2. The combination with the roller and curtain having a cross bar at its lower end, of an ornamental frame having channels at its opposite edges for the edges of the curtain and the ends of the cross bar, a sheet metal hood having a top and ends and projecting in front of and connected to the grate frame and receiving within it the roller and curtain, and the fingers or cross bar H, to guide the curtain, substantially as specified. 35 40 45

Signed by me this 1st day of April, 1893.

JAMES H. WHITE.
